UNITED STATES PATENT OFFICE.

JAY F. LANING, OF NORWALK, OHIO.

MANIFOLD SALES-BOOK.

SPECIFICATION forming part of Letters Patent No. 722,593, dated March 10, 1903.

Application filed February 5, 1902. Serial No. 92,760. (No model.)

To all whom it may concern:

Be it known that I, JAY F. LANING, a citizen of the United States, and a resident of Norwalk, county of Huron, State of Ohio, have 5 invented certain new and useful Improvements in Manifold Sales-Books, of which I hereby declare the following to be a full, clear, and exact description, such as will enable others skilled in the art to which it appertains to 10 make and use the same.

My invention relates to improvements in manifold sales-books; and the objects of the invention are to provide a simple and efficient form of book which will serve as a veritable 15 check upon dishonest clerks, since the leaves are printed in sections and no one leaf can be removed from the book or any section thereof without the instant detection of the management. I accomplish this object by composing 20 each book or section thereof of one continuously-doubled strip of paper, forming when folded a plurality of leaves, so that the identity of each section cannot be destroyed unless all the leaves composing the section 25 are removed. Again, the strips of paper are printed while integrally connected to form the consecutive, original, and duplicate leaves or pages and after doubling compose one section. Hence when binding or stapling the 30 book it would be impossible to omit one leaf without omitting an entire section, and if any one leaf were missing it would obviously be the fault of the clerk or at any rate must have been torn out after the book had been 35 put together and could not have been omitted by the binder. Of course if a whole section were omitted it would have been done by the binder unless the remaining stubs, which are also numbered, should show that 40 the leaves were removed after binding. To accomplish these objects, I construct the book as shown in the accompanying drawings, hereinafter described, and specifically pointed out in the claim.

45 In the drawings, Figure 1 shows a view of a completed book formed of two sections, each continuously folded into four leaves and duplicates from one integral strip. The lower extremity has been trimmed off, thus expos-

ing the free edges of all the leaves, the sections, however, being distinct at the upper ends. Fig. 2 shows an edge view of one of the sections. Fig. 3 shows a section formed of two strips of paper once doubled. Fig. 4 shows a section formed of two strips of paper, 55 one inclosing the other and the folded strips again doubled upon themselves, thus forming a section of eight leaves and duplicates. Fig. 5 shows a strip of paper once doubled to form two leaves and duplicates, and Fig. 6 60 shows a strip of paper made long enough to double three times repeatedly to form an eight-leaved section.

In the views, *a* is the first fold, *b* the second fold, and *c* the third fold. When complete, the lower half of each leaf *d* becomes the original and the upper half *e* becomes the duplicate. Space at *f* is left for stubs, which are numbered to correspond each with its leaf, so that any leaf taken out can be detected. 70 A line of perforations *g* separates the original from the duplicate, and another line *h* separates the duplicate from the stub. Staples *i* secure the stubs together. A carbon strip *j* is employed, as usual, in the manner 75 shown in Fig. 1. The strips of paper may be doubled repeatedly as many times as desired, care being taken to build each book of sections having the same number of leaves, and the purchaser is notified of the number of 80 leaves in each section. It will readily be seen that every time the sections are doubled the number of leaves are doubled and the security increased, since while a clerk might tear out one leaf he would hardly tear out four or 85 eight leaves, and tearing out one leaf would mar an entire section, as the consecutive numbers would show, and the omission could not have been made by the printer. After the books are bound and all danger of losing a 90 leaf is over the lower ends can be cut before delivery to the purchaser, as on line *Z* *Z*, or may be cut in the store.

Having described my invention, what I claim as new, and desire to secure by Letters 95 Patent, is—

In a manifolding sales-book a section therefor composed of an integral strip of paper re-

peatedly doubled in one direction, forming original and duplicate pages, a line of perforations separating the pages, a stub at one end of each duplicate page, and a line of perforations between each stub and the duplicate page adjoining, substantially as described.

5 In testimony whereof I have signed my

name to this specification in the presence of two subscribing witnesses.

JAY F. LANING.
